UNITED STATES PATENT OFFICE.

ALEXANDER BARON, OF BROOKLYN, NEW YORK.

DESIGN FOR A HOLSTER FOR TOY PISTOLS.

59,536.

Specification for Design.

Patented Nov. 1, 1921.

Application filed December 17, 1920. Serial No. 431,494. Term of patent 7 years.

To all whom it may concern:

Be it known that I, ALEXANDER BARON, a citizen of the United States, residing in the borough of Brooklyn, county of Kings, city and State of New York, have invented a new, original, and ornamental Design for Holsters for Toy Pistols, of which the following is a specification, reference being had to the accompanying drawing, forming part thereof.

Figure 1, is a front elevation, and Fig. 2, is an edge view of a holster for toy pistols, showing my new design.

I claim:

The ornamental design for a holster for toy pistols, as shown.

ALEXANDER BARON.

In presence of—
ISRAEL ELLIS.
